UNITED STATES PATENT OFFICE.

ALBERT J. LOEPSINGER, OF PROVIDENCE, RHODE ISLAND.

DRY-PIPE SPRINKLER SYSTEM.

Application filed June 22, 1923. Serial No. 647,174.

This invention relates to dry pipe systems for plural liquids such as may be used in automatic sprinkler fire extinguishing apparatus, discharging liquids operating by chemical reaction. Such systems employ two liquids, one of which is ordinarily an acid and the other an alkali, which react together immediately on mixing. For this reason and because the acid is corrosive it is especially desirable to employ the dry pipe principle, in which the pipes remain normally filled with air until a sprinkler opens from the heat of a fire, whereupon the reduction of air pressure automatically trips a valve for each liquid, to admit it to its system of piping leading to the sprinklers. In such cases it is highly desirable that both liquids, travelling through their respective systems, should arrive at the open head at the same instant, as the required effect is produced only by mixing, and as either alone may be seriously damaging to goods on which it may fall. It has, however, heretofore been found practically impossible to build two systems thus in parallel so that the valves will operate simultaneously. The present invention has for its object to provide means for the simultaneous operation of the separate valves controlling the liquids of such a system.

This object is accomplished by providing an operative connection between the two such that either may trip the other, or, more strictly, such that the tripping of either occasions the simultaneous tripping of the other. This is attained by providing a physical connection between operating parts of the two valves. The invention is here illustrated as it may be applied to a well-known type of dry pipe valve in which the liquid retaining clapper is held seated against the hydrostatic pressure of liquid by a system of linkage which is balanced in unstable equilibrium so that it yields upon slight dislodgement, and there is a weight, held suspended by air pressure in the distribution system, ready when released by fall of the air pressure to descend and knock the linkage system out of its said equilibrium, thus allowing the hydrostatic pressure to open the valve. The area of the yielding member which is exposed to the air pressure in the distribution system is so designed, with relation to the constant force applied to it by the weight, that the two are balanced when the air pressure has fallen, as it does upon the opening of a sprinkler anywhere in the system, to a certain predetermined value, which may, for example, be one-sixth of the normal hydrostatic pressure of liquid. With further falling the air pressure becomes too weak to hold the weight which thereupon descends, allowing the liquid valve to open. Where two such valves are side by side, each opening into its own distribution system, the fall of air may be a little slower in one system than in the other, or there may be slightly more friction in the linkage of one system than in the other, or, for other causes, the two, if entirely independent, may not have their valves tripped precisely simultaneously, even though the air release from them begins simultaneously on the opening of a double sprinkler head. It is a feature of the invention to make this action of the valves simultaneous, notwithstanding such differences; and this is accomplished by providing a mechanical connection between the parts which move when the valve is tripped. Specifically, the connection herein illustrated is made by replacing the separate weight supporting levers of both systems of linkage by a common lever having arms adapted to function as the single levers replaced. In the form illustrated this end is attained by arranging the two valves in physical proximity side by side so that like members of their systems of linkage move parallel with each other. The single weight supporting lever is suspended on both systems, and carries a weight sufficiently large to overcome the air pressure normally exerted on either air clapper alone, but small enough to be supported by the combined force of normal air pressure on both. It follows that when the air support of one system becomes sufficiently weak, even though the air support of the other system has not quite reached the necessary weakness, the combined loss in both systems will enable the weight to overcome the remaining pressure whereupon the tripping of both valves will occur simultaneously.

It will be understood that mechanical connections may be made in other respects between the parts which move when the tripping occurs, with similar results and within the scope of the invention. It will moreover, be understood that connections

may be made in other than mechanical respects between the two dry pipe and distribution systems which are desired to act as a single system, in order to produce simultaneousness of tripping as, for example, fluid connections between the air systems of a mechanical valve or of a differential valve, or between the intermediate chambers of either kind of valve. The generic invention, and the other species thereof thus mentioned are set forth and claimed in three other applications for Patent Serial Nos. 647,172; 647,173; and 647,175, filed coincidentally herewith. It is intended that the present patent shall cover, by suitable expression in the appended claims, whatever features of patentable novelty exist in the general idea of a mechanical connection between parts of the tripping mechanism and especially in the specific applications thereof herein disclosed.

In the accompanying drawing:—

Figure 1 is an elevation, partly in section, illustrating the application of the invention to the pipes and dry pipe valves of a sprinkler system; and

Figure 2 is a similar elevation, looking from the right in Figure 1.

Referring to the drawing, the figures show the beginning of two liquid distribution systems, 13, 23, arranged in parallelism, such as may be used, the one for carrying an acid and the other for carrying an alkali liquid to sprinklers where the alkali and the acid are jettied together or otherwise mixed so as to produce a fire extinguishing liquid, gas or foam formation in the manner well known. The dry pipe valves 14 and 24 illustrated are also of a type which are well known and therefore do not need to be described in detail.

In each case the liquid-retaining clapper 24" is held closed by a system of linkage including a toggle 55 held by a plunger 50 extending through an opening 48 in the wall of the intermediate chamber 49 into engagement with a lever 51, pivoted on the fixed frame of the valve. This lever is retained in plunger holding position by a strut 53 pivotally mounted on a lever 60 whose arms 61 and 62 are arranged to withdraw the plungers of both valves simultaneously when the lever 60 is permitted to swing under the influence of its weight 63. The weight carrying lever 60 when set to be tripped, is at 64 and 66 hooked on the power ends of trip levers 44, whose work ends tend to open the air clapper valves 46 with which they are individually associated and which are normally held to their seats by the air pressure in the systems. When the systems are full of air at the normally maintained pressure, the air clappers will remain closed, for the weight 63 is not large enough to overcome the combined normal pressures on the

two air clappers; but whenever the air pressure in either or both systems falls to a predetermined amount, as after the opening of a sprinkler, so that the combined moment exerted by the two air clappers on the work ends of the trip levers 44 is less than the moment exerted on these levers by the weight 60, the air clappers will be lifted. The incidental tipping of the trip levers 44 lets the hooks slip off from them and allows the weight 63 to fall. This swings the struts 53, which have been on dead centers, clear of the levers 51, and arms 61 and 62 withdraw the plungers 50; thus breaking the toggle and permitting both liquids to rush simultaneously into their respective distribution systems.

The two connected dry pipe valves are shown arranged with their weighted levers 60 in a common chamber 47, which intervenes between intermediate chambers 49 of the valves and connects them through openings 48 in which the toggle plungers 50 operate. The provision of the common chamber enables the pressure in the intermediate chambers of the valves to be equalized. When the linkage is set to hold the liquid clappers closed, the openings 48 in the valve casings proper through which the toggle plungers 50 project from chambers 49 into 47 are large enough to allow free passage of fluid, and the contents are kept at atmospheric pressure by the usual ball drip valve (not shown) which closes when a rush of fluid through it begins. The chamber thus affords fluid connection such that if either liquid valve were tripped enough to leak, and the other still held, the inflow of liquid would quickly fill the chamber and apply high pressure to the under side of the hesitating air valve 46, thus insuring its immediate opening and the simultaneous full release of both liquid valves 24".

It is desirable for the perfect simultaneousness of action that there be a communicating passage as indicated at 32, between the risers 13 and 23, or elsewhere between the air portion of the two systems, so as to provide equality of air pressure on the air clappers 46 of the two dry pipe valves. Upon the opening of the dry pipe valves and the rush of liquid through the risers 13 and 23 a small quantity of liquid from each flows into the connection 32. The gas formed at the place of meeting prevents further mingling of the liquids there; and the maintenance of this gas separation may be aided by providing a medial chamber 32' in which the gas is entrapped. With such a communicating passage, the connection to the air clapper chambers can be made from either riser and is here illustrated as a pipe 39 from riser 13 having branches 39' leading to the chambers above the air clappers 46.

The invention can also be used with an ac-

celerator 34 whose entrance pipe 35 is shown connected through branches 35' with each branch 39' of pipe 39 at a point between an air clapper chamber and a restriction 39" in 5 the branch. These restrictions are openings large enough to transmit a characteristic drop in pressure in the distribution systems 12, 23, through 39, 39', 35', and 35 to the accelerator to cause actuation of the latter, when a 10 sprinkler opens; but on the other hand are small enough to hold back air in 39 while unrestricted flow through 35' and 35 and the accelerator reduces the effective pressure in the chambers above the air clappers. This 15 may pass through the pipe 36 into either of the intermediate chambers 49, from which, by way of the common chamber 47 and passages 48 by the plungers 50, the fluid quickly reaches, and balances, the pressure on the 20 air clappers 46 so that the weights can fall. However a mere falling of the pressure above the air clappers is sufficient, whether the contents pass into the intermediate chamber as shown or into atmosphere. Upon the 25 tripping of the weighted levers each passage around the plunger 50 is closed, for each plunger in moving draws with it a plug collar 50' which seals the openings 48 in the wall of its chamber 49 and thereby prevents 30 leakage of either liquid into the connecting chamber and into contact with the other liquid.

I claim as my invention:—

1. In a dry pipe system for plural liquids, 35 having a separate distributing system and dry pipe valve for each liquid, the combination of two control systems of linkage, one for each valve, which have one of their controlling elements in common; the whole comprising means operative through the common element, upon reduction of pressure in either distributing system, to trip said linkage whereby both valves are opened at the same time.

2. In a dry pipe system for plural liquids, 45 having a separate distributing system and dry pipe valve for each liquid, the combination of two colored systems of linkage, one for each valve, which have in common a weighted lever adapted to maintain both valves closed while suspended and adapted to permit both valves to open simultaneously upon being tripped, and means operative upon reduction of pressure in either distributing system to trip said lever.

3. In a dry pipe system for plural liquids, 50 having a separate dry pipe valve for each liquid, the combination of two control systems of linkage, one for each valve, which have one of their controlling elements in common; said common element being opposed to the combined pressures of the distributing systems of the two liquids, and arranged to trip upon reduction of said combined pressure to a predetermined point,

whereby both valves are opened simultaneously.

4. In a dry pipe system for plural liquids having a separate dry pipe valve for each liquid, the combination of two control systems of linkage, one for each valve, which are separate except that they have in common a single weighted lever arranged to oppose the combined pressures of the distributing systems of the two liquids, and to trip upon reduction of said combined pressure to a predetermined point, whereby both valves are opened simultaneously.

5. In a dry pipe system for plural liquids, 70 having for each liquid a separate distributing system and dry pipe valve with auxiliary clapper seated by system air pressure, the combination of two control systems, one for each valve, having in common a control element which when set is restrained by the total of air pressure on the two said clappers; there being free liquid connection between the under sides of said clappers, whereby the fluid pressure thereon tending to open the valves is uniform.

6. In a dry pipe system for plural liquids, 75 having for each liquid a separate distributing system and dry pipe valve with auxiliary clapper seated by system air pressure, the combination of two control systems, one for each valve, having in common a control element which when set is restrained by the total of air pressure on the two said clappers; there being free fluid connection between the said air pressure sides of said clappers.

7. In a dry pipe system for plural liquids, 80 having a separate distributing system and dry pipe valve for each liquid the combination, with the auxiliary clapper for each distributing system adapted to be seated by system air pressure, and a weighted lever common to the two control systems arranged to oppose the combined pressures on said clappers, and to let both valves open upon the overcoming thereof, of means providing free fluid connection between the under sides of said clappers, and means providing free fluid connection between the upper sides of said clapper, whereby the fluid pressures 85 acting on said clappers are uniform on both said clappers.

8. A dry pipe system for plural liquids, 90 having a separate distributing system and dry pipe valve for each liquid, in which the control system of the two dry pipe valves have in common an accelerator on the air pressure side connected to one of said distributing systems for its own actuation and arranged to relieve the pressure on both air clappers simultaneously and equally; and a weighted lever on the intermediate chamber side, adapted to oppose the combined pressures on said clappers so that upon fall of said combined pressures to a predetermined 95

degree said lever will trip and cause simultaneous opening of both dry pipe valves.

9. In a dry pipe system for plural liquids, having a separate distributing system and 5 dry pipe valve for each liquid, the combination or two control systems of linkage, one for each valve, which have in common a weighted lever adapted to be held suspended by the air pressures in the two distribution systems, and to overcome the air pressure of a single distribution system, so that 10 upon fall of the air pressure in either system to a predetermined degree, said lever will trip and cause simultaneous opening of 15 both dry pipe valves.

10. In a dry pipe system for plural liquids, having a separate distributing system and dry pipe valve for each liquid, the combination of two control systems of linkage, one for each valve, arranged side by side and 20 operating in like directions of rotation about axes which are parallel, and being interconnected; the whole comprising means operative, upon reduction of pressure in either distributing system, to trip said linkage 25 whereby both valves are opened at the same time.

Signed at Boston, Massachusetts, this 18th day of May, 1923.

ALBERT J. LOEPSINGER.

Certificate of Correction.

It is hereby certified that Letters Patent No. 1,596,280, granted August 17, 1926, upon the application of Albert J. Loepsinger, of Providence, Rhode Island, for an improvement in "Dry-Pipe Sprinkler Systems," were erroneously issued to the inventor, said "Loepsinger," whereas said Letters Patent should have been issued to *General Fire Extinguisher Company, of Providence, R. I., a Corporation of Delaware*, said corporation being assignee, by mesne assignments, of the entire interest in said invention, as shown by the records of assignments in this office; and that the said Letters Patent should be read with this correction therein that the same may conform to the record of the case in the Patent Office.

Signed and sealed this 9th day of November, A. D. 1926.

[SEAL.]

WM. A. KINNAN,
Acting Commissioner of Patents.
